CONSTRUCTION OF ELECTRIC DEVICES

Filed Aug. 3, 1926

Inventor:
Márcello Pirani,
by *Alexander S. Ladd*
His Attorney.

UNITED STATES PATENT OFFICE

MARCELLO PIRANI, OF BERLIN-WILMERSDORF, GERMANY, ASSIGNOR TO GENERAL ELECTRIC COMPANY, A CORPORATION OF NEW YORK

CONSTRUCTION OF ELECTRIC DEVICES

Application filed August 3, 1926, Serial No. 126,873, and in Germany March 30, 1926.

The present invention relates to electrical devices having a hot filament, and more particularly to high current electric lamps, vacuum tubes and the like.

- 5 It is an object of my invention to provide electrical devices such as electric lamps with the neck made in sections of metal and a vitreous insulating material such as glass. Another object of the invention is to provide 10 the metal sections of the neck with cooling devices and to fasten to these metal sections the lead wires which in the interior of the lamp, in the case of electric lamps, serve to support the filament. Furthermore, the lead 15 wires may be rigidly fastened to the cooled metal sections, thereby insuring rigidity and stability inasmuch as the usual sealing of leading-in wires into glass is done away with.

The invention and its details will be more 20 readily understood from the accompanying specification, claims and drawing, in which drawing the figure shows one form of an incandescent lamp in elevation and in section.

Referring more in detail to the drawing it 25 will be seen that the neck of the glass bulb *r* of the lamp comprises a metal annulus or short tube *c* constituting one terminal of the lamp and sealed between the glass tube or section *a* of the bulb on one side and the glass 30 tube or section *b* of the neck on the other side, the lower part of the section *b* being folded within the neck to form a reentrant inner glass stem or tube *f*.

Within the neck of the lamp there is a 35 second metal tube *g* which is sealed at its outer end to the glass stem *f* of the neck, so that its inner end is inside the neck and adjacent the metal annulus or short tube *c*, which may be threaded on the inside to support a 40 ring *d* from which a lead wire *e* projects into the bulb.

The tube or annulus *c* is also threaded on the outside to support a hollow cooling element, such as a tubular collar *l*, thru which a 45 liquid or other cooling medium may be caused

to flow. For this purpose the collar is provided with an inlet tube *m* and an outlet tube *n*. It will be understood that in order to effectively seal the metal tubes *c* and *g* to the glass the ends of the tubes should be sharp. 50 The inner end of the metal tube *g* is joined to a second terminal inside the neck and comprising a head *h* which closes air-tight the inner end of the tube *g* and from the outer side of which a metal pipe *k* projects to a 55 point outside the neck. From the inner side of said head *h* of the second terminal, a second lead wire *i* projects into the bulb. The filament *s* is connected to the two lead wires *e* and *i* to form a bridge between them. 60 The metal tube *g* with the head *h* forms a skirt with its inner end adjacent the metal annulus or terminal *c* and its outer end hermetically sealed to the stem or tube *f* which forms part of the vitreous section *b* 65 of the neck. The pipe *k* and the head *h* which closes it at its inner end form a hollow terminal having the shape of a deep cup placed inside of and concentric with the skirt *g*. The pipe *k* has at its outer end a hollow 70 cooling element or cap *p* provided with an inlet connection *t* and an outlet connection *u* for the purpose of causing a cooling medium, such as water, to flow thru the hollow terminal. The metal skirt *g* is secured by the head 75 *h* to the inner end of the hollow terminal and extends along it, with the free end of the skirt directed toward the middle of the hollow terminal. The cap *p* is provided with a binding post *v* which latter is in electrical 80 connection thru the metal cap *p* with the metal pipe *k* of the hollow terminal and hence with the lead wire *i* within the lamp. Similarly the hollow collar *l* is provided with a binding post *o* which is electrically connected 85 with the metal annulus and with the lead wire *e*. With this construction the two terminals and therefore the lead wires *e* and *i* between which the filament is connected may be kept at a comparatively low tem- 90

perature notwithstanding the use of a large volume of current.

While I have elected to disclose my invention in connection with these specific forms of construction shown in the drawing, I do not wish to be limited to these particular forms inasmuch as the invention may be used in connection with other forms without departing from the scope of the claims herein. For example, in place of the elements shown for water cooling there may be used an air cooling arrangement with ribs, ducts and the like.

What I claim as new and desire to secure by Letters Patent of the United States, is,—

1. A high current hot filament device comprising a glass bulb having a neck, formed of a metal tube sealed between two tubular glass sections, one terminating in said bulb at one end and the other having one end sealed to said metal tube and the other end thereof folded within said neck to form a tubular stem, a second metal tube within said first metal tube sealed to the end of said tubular glass stem within said neck, a filament within said bulb mounted in bridge between said metal tubes, and a cooling element attached to each of said metal tubes whereby they may be maintained cool by causing a cooling fluid to flow therethrough, said cooling elements serving as terminals for the device.

2. A high current hot filament device having a bulb with a tubular neck, a filament located within said bulb, a terminal for said filament on the outside of said neck, a terminal for said filament on the inside of said neck, a cooling element on the outside of said neck for cooling said first terminal, and a cooling element for cooling said second terminal, said cooling elements being hollow whereby a cooling fluid may be caused to circulate therethrough.

3. An incandescent lamp or similar device comprising a bulb with a neck comprising two tubular vitreous sections and a metal annulus between said vitreous sections with its ends hermetically sealed to said sections and constituting one terminal, a second terminal projecting into said neck and having the shape of a deep inverted cup with a metal head at the bottom of said cup, a tubular metal skirt joined air-tight at one end to said head to be concentric with and to extend along said second terminal with its other end opposite the middle part of said second terminal and hermetically sealed to the outer one of said vitreous sections, a filament lead projecting from each of said terminals, and a filament connected between said leads.

4. An incandescent lamp or similar device comprising a bulb with a tubular neck comprising two annular vitreous sections and a metal annulus between said sections constituting a terminal hermetically sealed at its end to said vitreous sections, a tubular metal skirt hermetically sealed at its outer end to

the outer vitreous section of said neck and having its inner end positioned inside said neck adjacent said metal annulus, a hollow terminal inside said skirt with its inner end joined to the inner end of said skirt, leads projecting from said terminals into said bulb, a filament connected between said leads, and cooling means for circulating a cooling fluid thru the interior of said hollow terminal.

In witness whereof, I have hereunto set my hand this 20th day of July, 1926.

MARCELLO PIRANI.
